UNITED STATES PATENT OFFICE.

WILFRID MATTHEW HARRISON, OF CHESHUNT, ENGLAND.

MEANS FOR VAPORIZING FUEL FOR INTERNAL-COMBUSTION ENGINES.

Application filed January 5, 1923. Serial No. 610,878.

To all whom it may concern:

Be it known that I, WILFRID MATTHEW HARRISON, a subject of the King of Great Britain and Ireland, residing at Cheshunt, in the county of Herts, England, have invented Improvements in Means for Vaporizing Fuel for Internal-Combustion Engines, of which the following is a specification.

This invention, which is directed to the vaporizing of fuel for internal combustion engines, relates to means of the kind wherein in a self contained flange device, carrying an electric heating element, is adapted to be interposed between, say a carburetter and the induction pipe of the engine, so that the heating element enters the duct conveying the explosive mixture to the cylinder or cylinders. Many proposals of this general kind are known but as far as I am aware none satisfactorily meets the various requirements of modern practice which include a minimum of obstruction to the flow of mixture, a resistance element which is so protected that the mixture cannot come in contact therewith even in case of accident, whereby fire risk is avoided, and as effective a heating of the wall of the duct as possible in order to prevent condensation in the duct and on the wall thereof of vapour after it has formed.

All these features in combination are present in electrical heating means according to the present invention which comprises a length of resistance material, such as nichrome wire or strip, covered with insulation material, as for instance asbestos and enclosed within a metal casing.

The composite electrical heating element thus constituted is caused to assume a crenelated or a zigzag loop shape and is bent as a whole to a circular shape and fixed to a flange-like carrier, the projecting portions of the heating element remote from the flange carrier, which resemble fingers, being bent outwardly so that when the carrier is placed in position with the heating device extending into the induction pipe or duct of an engine, the fingers will bear snugly against the inner surface of the pipe at different parts therof, and effectually heat the pipe when the heating element is switched into circuit with a battery, the said heating element at the same time offering practically no obstruction to vapour flowing through and past it.

The casing may be produced by electrical

deposition of metal upon or over the insulated length of insulated resistance material, suitably prepared for the purpose, or, as is preferred, by covering the insulated length of resistance material with a copper tube drawn out over the length of insulated resistance material until it forms almost or quite a tight fit therewith. The heating element thus constituted is then bent into the form mentioned for insertion into the induction pipe of an engine, or into the carburetter, or into both thereof.

The invention is capable of being variously carried into effect and the details of construction modified without departing from the scope of the invention but it will suffice to describe two specific forms with reference to the accompanying drawings, whereof Fig. 1 is a part sectional elevation of a portion of one form of device as it appears at an intermediate stage in the manufacture thereof. Fig. 2 is a plan of the device complete and Fig. 3 is a section on the line 3—3 Fig. 2. Fig. 4 is a perspective view of the second form of device which is of simplified construction and Fig. 5 is a section, or into both thereof.

In each case a convenient form of heater is obtainable by taking a length *a* of resistance material such as nichrome wire or strip and bending or folding the same so that in outline it resembles an embattlement. The heating element thus constituted is housed in a suitable metal casing. In the first example the casing *b* has a series of pockets *b'* extending parallel to one another laterally from a straight region *c* adapted to be bent circularly so that when inserted into the induction pipe or fuel duct the pockets extend parallel to the axis of such pipe or duct. The casing referred to may be carried by a flange member *d* of insulating material in which holes *e* are or can be made to suit those of existing carburetter flanges, the said insulating flange being provided with terminals *f* for connection to the electrical source of supply. It is preferred that after the casing has been bent the pockets *b'* should have a slight divergence as shown in Fig. 3 necessitating them being to a certain extent sprung before they can be inserted in the pipe or duct, their natural elasticity thereafter causing them to snugly bear against the metal of the pipe or duct. In this way danger of overheating is avoided and the raising of the temperature of the

pipe is ensured. The casing may be made in any suitable way and confines both the heating element *a* and a surrounding or enveloping layer *g* of insulating material 5 which may be asbestos impregnated or not with sodium silicate for example. As it is or may be desirable that the casing should be gas tight, the same may be completed or entirely produced by the electrical deposition 10 of metal upon or over the insulated heating element. The casing may be fastened to the insulating flange member *d* in any convenient way such as by forming or providing the former with a ledge or rim *h*, 15 saw cut at intervals so that when the casing is bent it forms an external peripheral margin which can be sprung into position within a circumferential groove in the flange member as shown in Fig. 3, the length of the 20 casing being selected to permit of this being done. The ends of the heating element *a* may pass from the casing in any suitable way, being reinforced if desired in order to obtain mechanical strength and prevent 25 overheating.

The second form of device shown in Figs. 4 and 5 and which may be preferred on account of its simple construction is produced by enclosing an insulated nichrome 30 or like resistance wire *a*¹ within a tubular metal casing *i* and then bending the same to the shape shown. The ends *j* of the said casing are inserted into holes in the insulating flange *d* so that it is supported therefrom with embattlement like loops projecting in a manner which enables them to be inserted in and make contact with the walls of the duct as already referred to. The heating elements *a*¹ may advantageously be 40 encased by employing a copper or like tube of appropriately large diameter to permit of the insulated wire being passed therethrough and then by a drawing operation to stretch and gradually diminish the diameter of the tube until it envelops the insulated wire and makes intimate contact therewith.

If desired and as shown in Fig. 3 a wire gauze or perforated member *k* may be employed which will act to atomize the mixture, to deflect a large proportion of the mixture into contact with the heater, to disseminate heat to the mixture by conduction and to prevent flame from any cause firing 55 back to the carburetter.

Said device *k* may appropriately be of truncated conical form with a disc *m* at the smaller end, and arranged so that the disc is in advance of the base considering the 60 engine cylinder; as exemplified the device *k* is formed with a margin or rim *n* to enable it to be clamped to the insulating flange *d* by the ledge or rim *h* of the casing *bc*.

As will be obvious the heater according to the present invention will raise the temperature within the pipe or fuel duct more rapidly than does an external heater and quicker starting will result but the heating means should be left in circuit for a greater length of time after starting in order to thoroughly heat the surroundings of the mixing chamber or it may be found that there is an immediate falling off in power before the engine has been running long enough to supply its own heat to the mixture. In the case 75 of the external heater this thorough warming requires to be effected before starting is attempted.

What I claim is:—

1. In an internal combustion engine, a 80 conduit and an electrical heater adapted to be inserted in said conduit, the heater comprising a length of resistance material, a covering of insulating material and an enclosing casing of metal, the casing being 85 subsequently bent to a circular form so as to uniformly engage the inner wall of the conduit.

2. In an internal combustion engine, a 90 conduit and an electrical heater adapted to be inserted in said conduit, the heater comprising a length of resistance material, a covering of insulating material and an enclosing casing of metal, the casing being 95 subsequently bent into a zig-zag and circular form so that the zig-zag portions uniformly engage the inner wall of the conduit.

3. In a fuel heater for the induction pipe of an internal combustion engine or like 100 conduit, a length of insulated resistance wire and a metallic casing therefor comprising a tube which by a process of drawing is stretched over the insulated wire so as to pass tightly upon the latter, the said casing being 105 subsequently bent in opposite directions alternately, substantially as described.

4. A fuel heater for the induction pipe of an internal combustion engine or like conduit, comprising a length of insulated resistance wire over which is drawn a tubular metal casing, the said casing being bent into a zig-zag formation and the whole thereafter bent into a form such that the several loops are each adapted to make contact with part of the internal wall of the conduit, a flange member adapted to be secured to the conduit to form a continuation thereof and to support the casing in the conduit, and terminals upon said flange member connected to the resistance wire and by means of which an electric current can be conducted thereto substantially as described.

Signed at London, England, this 20th day of December, 1922.

WILFRID MATTHEW HARRISON.
